199,378

MEMORIAL MARKER

Paul R. Irr, Pittsburgh, Pa.
(Queen of Heaven Cemetery, Rte. 19, Bridgeville, Pa.)

Filed Dec. 6, 1962, Ser. No. 72,744

Term of patent 14 years

(Cl. D79—2)

Fig. 1.

Fig. 2.

FIGURE 1 is a top plan view of a memorial marker according to my invention.

FIGURE 2 is a side elevation of the marker of FIGURE 1.

The dominant features of my design reside in the portions shown in full lines.

I claim:

The ornamental design for a memorial marker, as shown and described.

References Cited by the Examiner

UNITED STATES PATENTS

D. 179,854 3/57 Livers ----- D79—2

OTHER REFERENCES

Prayer Books and Accessories Catalog No. 6, © 1948, page 144, illustration showing angels at center left of page.

Hirten of New York Catalog for 1943, page 25, item No. D-61.

ADELINE B. HANNAH, Primary Examiner.